METHOD AND APPARATUS FOR
CONDITIONING AIR

Edward T. Turner, Dayton, Ohio

Application June 25, 1934, Serial No. 732,240

41 Claims. (Cl. 257—1)

This invention relates to a method and apparatus for conditioning air and is designed more particularly for residential air conditioning although it is not limited to such use.

One object of the invention is to provide a simple and efficient method of conditioning air which can be carried out at a low cost, thereby making residential air conditioning available to persons of moderate means.

10 A further object of the invention is to provide a method of air conditioning in which waste air will be utilized in modifying the temperature of the air which is to be conditioned.

15 A further object of the invention is to provide a method of heat exchange whereby the heat of one fluid may be efficiently transferred to a second fluid.

20 A further object of the invention is to provide a simple and efficient method of modifying the dew point temperature of fresh air which is to be supplied to a room.

25 A further object of the invention is to provide a method of air conditioning in which the dew point temperature of fresh air to be supplied to a room will be progressively varied in a plurality of successive operations.

30 A further object of the invention is to provide a method of conditioning air wherein the fluid used to modify the dew point temperature of fresh air may be utilized to modify the dry bulb temperature of air which is to be delivered to a room.

35 A further object of the invention is to provide a method of air conditioning in which the fluid employed will be progressively cooled by a plurality of successive operations, thereby lowering the cost of refrigeration.

40 A further object of the invention is to provide a method of heating air whereby the desired temperature may be secured at a low fuel cost.

45 A further object of the invention is to provide apparatus for performing the method which will be of a simple inexpensive construction and which may be operated at a low cost.

50 Other objects of the invention will appear as the method and apparatus are described in detail.

In the accompanying drawings Fig. 1 is a sectional view, partly in elevation, of one form of apparatus for carrying out my invention; Fig. 2 is a sectional detail view of a controlling valve; Fig. 3 is a sectional view, partly in elevation, of another form of apparatus for carrying out the method; Fig. 4 is a sectional detail view of a portion of a baffle; and Fig. 5, is a sectional view,

partly in elevation, of a third form of apparatus for carrying out my invention.

In these drawings I have shown certain forms of apparatus as illustrative of the various ways in which the several steps of the method may be performed. In an air conditioning apparatus it is preferable to withdraw from the room to which conditioned air is being supplied a quantity of old air and after this room air has been reconditioned to return it to the room, and in each of the several forms of apparatus here shown I have provided a main air conduit for this purpose. In Fig. 1 the main air conduit is shown at 5 and communicates at one end with an outlet 6 in the floor of the room and communicates at its other end with one or more inlets 7 leading to the room. It will be understood that the term "room" as herein used is intended to include any enclosure to which conditioned air is to be supplied and that it may comprise one compartment or a plurality of compartments. In the form here shown this conduit is of a U-shape and is provided with a motor driven fan 8 for circulating the room air through the same, this fan being in the present instance arranged near the outlet end of the conduit. It is also important that a sufficient quantity of fresh air should be supplied to the room and, preferably, a fresh air conduit 9 is connected with the main or room air conduit 5 at some suitable point. As here shown, this fresh air conduit is connected with the main conduit in advance of the fan 8 so that that fan will serve to draw the fresh air through conduit 9. There must, of course, be discharged from the room, to waste, a quantity of old or room air corresponding to the quantity of fresh air introduced into the room. This waste air may be discharged through any suitable outlet but, in the present construction, I have shown a waste air conduit 10 connected with the main conduit as 10 this facilitates the utilization of the waste air in a manner which will be hereinafter described. If desired, the waste air conduit may be arranged just beyond the fan 8 so that a portion of the air will be forced from the main conduit through 15 the waste air conduit by the fan.

The fresh air is treated, by subjecting it to the action of a liquid, to impart thereto a pre-determined dew point temperature prior to its being mixed with the room air in the main conduit 5. The liquid used for this purpose may be of any suitable character but preferably water is used. A continuous supply of fresh cool water may be utilized for modifying the dew point temperature of the air or the same water may

be recirculated through the system and cooled after each passage through the air. Where an ample supply of cool water is available at low cost the first mentioned or fresh water system 5 is usually preferable and in that form of the apparatus shown in Fig. 1 I have employed a fresh water system and have shown a pump 11 for lifting the water from a well 12 and delivering the same to the humidifying device, which is 10 indicated as a whole by the reference numeral 100. It will be obvious, however, that the water may be taken from any suitable source and when taken from a water system it will usually be under sufficient pressure to avoid the necessity of 15 using a pump 11. The device 100 for imparting the desired dew point temperature to the fresh air, which is commonly called a humidifier, is of such a construction that the outgoing fresh air will have a dew point temperature closely approaching the temperature of the incoming water and the outgoing water will have a temperature closely approaching the wet bulb temperature of the incoming fresh air. This device preferably comprises a casing 13 having near one 20 end, in the present instance its lower end, an inlet 14 for fresh air which, as here shown, is connected with a fresh air supply pipe 15, and having near its other end an outlet 16 for the air, which is connected with the fresh air supply 25 pipe 9 leading to the main conduit 5. The casing may be of any suitable character and, in the present instance, it comprises merely an enlargement of the fresh air conduit. Water from the pump 11, or other source of supply, is delivered 30 through a supply pipe 17 into the upper portion of the casing and is there discharged through a distributor or spray head 18. The water discharged from the distributor 18 flows downwardly, in a direction opposite the direction 35 of flow of the air through the casing, and inasmuch as the casing is of larger diameter than the conduits 9 and 15 the air will flow relatively slowly through the same. In order to maintain this air in such contact with the water, or other 40 liquid, as to effect the desired heat exchange, the casing may be provided with a baffle over which the water flows. This baffle may be of any suitable character which will retard the flow of the water and spread the same into thin 45 sheets of water so that relatively large surface areas of the water will contact with the air. In the present construction, I have shown the baffle as comprising a body of coarse material, such, for example, as coke, as shown at 19. This coke 50 rests upon a screen 20 carried by a spider 21 arranged in the casing just above the air inlet 15. A second screen 22 is arranged between the baffle and the distributor 18 and serves to distribute the water throughout the entire cross sectional 55 area of the casing. In order that the proper heat transfer may be maintained between the air and the water, either with or without a baffle, it is important that the rate of flow of the water should be determined in accordance with the heat content of the air entering the casing. This may be accomplished by providing the supply pipe 17 with a restricted orifice, but when 60 the heat control of the incoming fresh air is subject to wide change it is desirable that the controlling device shall be of a character which can be adjusted as occasion demands, such as the valve 23. It is also desirable that this valve shall be automatically adjusted to maintain the proper flow of water through the casing 65 under all conditions and I have here shown a

valve adjusting device which is controlled in accordance with the temperature of the water discharged from the casing. As has been heretofore stated, the water passing through the casing countercurrent to the air will absorb heat 5 from the air, when the air is of a higher temperature than the water, so that the dew point temperature of the air at the outlet 16 will approximate the temperature of the water delivered to the casing. In a proper installation the dew 10 point temperature of the outgoing air may be only one or two degrees higher than the temperature of the water delivered to the casing. Likewise the water which is discharged from the casing will have a temperature only slightly lower than the wet bulb temperature of the incoming fresh air. In practice the water will have a temperature approximating the wet bulb temperature of the incoming air just before the initial contact of the fresh air with the water and 15 the temperature of the water will be slightly lowered by the fresh air before it is discharged, due to the partial evaporation of the water, unless the fresh air is saturated. The water is discharged from the casing into a suitable receptacle, such as a catch basin 24, here shown as formed integral with the casing and arranged just below the air inlet. The controlling valve 23 is actuated by a thermostatic device comprising a bellows 25 and a bulb 26, for a volatile 20 fluid, which is arranged in the catch basin 24. The bellows 25 is connected with the valve through a lever 27 in such a manner that when the temperature of the water in the catch basin rises, thus indicating a rise in the heat content 25 of the fresh air, the bellows 25 will expand and thus open the valve to provide an increased flow of water. It is desirable that the valve shall be of such a character that the flow of water will not at any time be completely 30 interrupted and that the area of the valve port will increase in direct ratio to the movement of the valve member. In the valve shown in Fig. 2 the valve member is in the form of a 35 slideable pin 28 adapted to extend into a valve 40 port 29 but of such a diameter that the port will not be completely closed when the pin is fully inserted therein. The end of the pin is tapered in such a manner that the area of the opening will increase in direct proportion to the outward movement thereof. The catch basin is connected with a discharge pipe 30 through which the water escapes therefrom and the outlet leading to this discharge pipe is controlled by a float operated valve 31 to maintain the water in the 45 catch basin at all times at a depth sufficient to 50 cover the bulb 26. When the water at the source of supply has a temperature lower than the desired dew point temperature for the fresh air it is delivered to the casing 13 without modification but should cold water not be available it may be necessary, in order to secure the desired dew point temperature in the air, to cool the water before it is delivered to the casing and for this purpose it may be passed through a 55 cooling element 32, which may be of any suitable character.

In heat exchangers of the character described herein, it is important, first, that the quantity of the water circulated through the system shall 60 be the smallest quantity which will effect the desired results and, second, that the temperature differential between the influent water and the effluent air shall be reduced to a minimum, that is, that the temperature of the air leaving the 65 70 75

conditioner shall closely approach the temperature of the incoming water. To enable the desired results to be attained with a minimum quantity of water, the temperature change of the water must be the maximum attainable and this in turn requires that the temperature of the effluent water shall closely approach the wet bulb temperature of the influent air. Thus in an efficient apparatus the temperature differential will be small and substantially the same at both ends of the apparatus.

The influent air becomes saturated when it contacts the effluent water and in a properly constructed apparatus having the correct flow of water, the air becomes saturated at this point substantially at its initial wet bulb temperature. For maximum efficiency the temperature change of the water should approximately equal the wet bulb temperature change of the air. In practical operation the wet bulb changes of the air will often be large, and for high efficiency, low water consumption, and low final wet bulb temperature, the temperature change of the water must be considerably more than the temperature differential. In an installation for domestic use it is often desirable to provide an apparatus in which the temperature change of the water will be from three to five times the temperature differentials.

To effect the relatively large temperature changes with respect to the temperature differentials it is important that the delivery of water to the apparatus be properly regulated, that the water shall flow counter-current to the air and shall be spread into thin sheets to provide large surface areas for contact with the air, and that the flow of water shall be retarded so that it does not appreciably oppose the free flow of the air.

The water, which is discharged from the casing 13 into the catch basin 24 at a temperature approximating the wet bulb temperature of the incoming fresh air, will have a temperature substantially lower than the dry bulb temperature of the room air and may therefore be utilized to cool the air which is to be delivered to the room, that is, in the present instance, the air which is circulating through the main conduit 5. For this purpose I have arranged within the conduit 5 a heat exchange element 33, here shown as a coil of pipe provided with fins 34. The water from the catch basin 24 is delivered to the upper end of the element 33 and thus caused to flow through that element in a direction opposite to the direction of flow of the air through the conduit 5. Any suitable means may be provided for circulating the water through the element 33 but preferably the discharge pipe 30 is connected with a pump 35, the outlet of which is connected by a pipe 38 with the upper end of the element 33. The lower or discharge end of the element 33 is connected with a waste pipe 37 which may be provided with a valve 38 for a purpose which will hereinafter appear. The quantity of the cool water flowing through the heat exchange element 33 may be controlled in accordance with the temperature of the room air and for this purpose I have provided the discharge pipe 30 with a branch pipe 39 which may lead to waste. This branch pipe is controlled by a valve 40 which is actuated by a thermostatic device which, in the present instance, comprises a bellows 41, operatively connected with the valve, and a bulb 42 arranged in the main conduit 5, the arrange-

ment being such that when the temperature of the air in the conduit 5 falls the bellows 41 will open the valve 40 and thus permit a portion of the water to escape to waste, so that a smaller quantity of water may be circulated through the cooling element 33. If desired, the discharge line 30 may be provided with a valve 43 so that the supply of water to the pump and cooling element may be cut off at will. The rate of flow of the water through the cooling element is so controlled as to bring about the desired exchange of heat, this being in the present instance accomplished by regulating the operation of the pump 35.

It may at times, particularly in hot weather, be desirable to pre-cool the fresh air before it is delivered to the heat exchange device or humidifier 100, in order to secure in the heat exchange device the desired dew point temperature without the use of an excessive amount of water. This pre-cooling of the fresh air may be effected at a very small operating cost by utilizing the waste air, which is discharged from the room, through the medium of a suitable heat exchange apparatus. In the construction here illustrated the heat exchange apparatus comprises two casings 44 and 45, which may, if desired, be arranged one above the other. One of these casings, in the present instance the lower casing 44, is provided with an inlet 46 for fresh air and an outlet 47 for fresh air, this outlet being connected with the fresh air supply pipe 15 which leads to the casing 13 of the humidifier or heat exchange device 100. In the form here shown the casing 44 is separate from and arranged above a catch basin 48, so that the fresh air may enter at the bottom of the casing. With this arrangement a supply pipe for fresh air is unnecessary and the air may be admitted to the basement, or other compartment in which the apparatus is installed, through a window 49. The second casing, 45, is provided near its lower end with an inlet 50 for room air which is here shown as connected with the waste air pipe 10. At its upper end this casing is provided with an outlet 51 for air. Both casings may, if desired, be provided with baffles, 52 and 53, similar to the baffle in the casing 13.

The water is withdrawn from the catch basin 48 by a pump 54 and is delivered through a pipe 55 to a distributor 56 in the upper portion of the upper casing 45 so that this water passes downwardly over the baffle 53 countercurrent to the room air, which is passing upwardly through the casing. In warm weather this room air will be at a temperature substantially lower than the outside temperature and the water passing through the same will be discharged into a catch basin 57 at a temperature approximating the wet bulb temperature of the incoming room air, this air being then discharged through a conduit 58 to the exterior of the building. The water is discharged from the catch basin 57 by gravity through a pipe 59 to a distributor 60 in the upper portion of the lower casing 44 and flows downwardly over the baffle 52 countercurrent to the fresh air, which is passing upwardly through the casing, thus causing the dew point temperature of the fresh air to be materially lowered, so that when delivered to the first mentioned heat exchange casing 13 it will have a relatively low dew point temperature. The water is discharged from the casing 44 into the catch basin 48 and it will thus be apparent that the water is circulated through an endless circuit a part of

which comprises the casing 45 through which the room air passes and another part of which comprises a casing 44 through which the fresh air passes. The rate of flow of the water may be 5 regulated to secure the desired heat exchange in any suitable manner. As here shown, this control is effected by a valve 61 which is controlled by a thermostatic device comprising a bellows 62 and a bulb 63 immersed in the water in the 10 catch basin 48. This pre-cooling of the fresh air before it is delivered to the heat exchange casing 13 will not only reduce the amount of water necessary to impart the final dew point temperature to this fresh air but will also cause the water 15 to be discharged from the casing 13 at a relatively low temperature and thus increase its cooling action on the air in the main conduit 5. In order to prevent the water which circulates through the casings 44 and 45 from becoming 20 stale I provide for a constant but slow change of that water. As here shown, a waste pipe 64 leads from the catch basin 48 and is provided with a restricted outlet 65 through which a small quantity of water will constantly flow. A constant 25 supply of fresh water is provided through a float controlled inlet valve 66.

Under some temperature conditions the passage of the fresh air through the heat exchange casing 44 may impart thereto the desired dew 30 point temperature, suitable for mixing with the room air in the main conduit 5, and under these circumstances the operation of the heat exchange device or humidifier 100 will be interrupted so that the casing 13 will merely constitute a portion 35 of the conduit leading from the casing 44 to the main conduit 5. This interruption may be effected by merely stopping the operation of the pump 11 or otherwise interrupting the supply of water to the casing. It will be obvious that in 40 cold weather the room air will have a temperature higher than the outside air and therefore action of the heat exchange apparatus 44-45 will serve to raise the temperature of the fresh air rather than to lower the same and the heat 45 exchange device or humidifier 100 need not be used. The apparatus thus automatically accommodates itself to exterior air conditions and the only action necessary on the part of an operator is to interrupt the operation of the heat exchange 50 device or humidifier 100 when this becomes desirable.

In cold weather the heat exchange element 33 in the main conduit 5 may be used for heating the air which is to be delivered to the room and 55 when this is to be done the valve 43 is closed to cut off the supply of cool water to the pump 35, and the valve 38 is closed to cut off the connection between the heat exchange element 33 and the waste line 37. The element 33 is then connected 60 in circuit with a similar element 67 arranged in a heater so that water, or other suitable liquid, will be heated in the heat exchange element 67 and cause to circulate through the element 33 in the conduit 5. In the arrangement here shown the 65 heater element 67 is connected at its lower or discharge end with a pipe 68 which leads to the pump 35 and is provided with a valve 69 by means of which the connection may be interrupted when the heat exchange element 33 is to be used for 70 cooling purposes. The upper or receiving end of the heating element 67 is connected by a pipe 70 with the lower or discharge end of the heat exchange element 33, this connection also being controlled by a valve, 71. The heater or furnace may 75 be of any suitable construction but I have here

illustrated it as comprising a casing or drum 72 in which the heat exchange element 67 is located and have arranged in the casing, below the element 67, a gas burner 73. It will be apparent therefore that the liquid will circulate through the heat exchange element 67 in a direction opposite the direction of flow of the products of combustion in the heater casing 72 and will flow through the heat exchange element 33 in a direction opposite the direction of flow of air through the main conduit, thus causing in each instance a relatively large exchange of heat. The operation of the gas burner 73 may be automatically controlled according to the temperature of the room air and, as here shown, a gas supply pipe 74 which leads to the burner 73 is provided with a valve 75 which is actuated by a bellows 76 connected by a pipe 77 with the bulb 62 in the main conduit 5, the arrangement being such that an increase in temperature of the air in the main 20 conduit 5 will cause the bellows 76 to expand and close or partially close the valve 75. If desired, the gas supply pipe 74 may also be provided with a valve 78 which is automatically operated to cut off the gas in the event of the excessive heating 25 of the liquid in the circuit. As here shown, this valve is actuated by a bellows 79 connected with a bulb 80 arranged in an enlargement or chamber 81 formed in the pipe 68 between the heating element 67 and the pump. Obviously if the 30 heater used solid fuel these thermostatically controlled devices would be connected with dampers instead of with valves. Means are also provided for reducing or interrupting the flow of liquid through the circuit when the liquid has been 35 excessively heated. To this end a valve 82 in the pipe 68 is actuated by a bellows 83 connected with a bulb 84 also located in the chamber 81.

The heater is constantly supplied with air which passes through the casing 72 and is discharged at a high temperature, usually passing to waste, and I have provided means for utilizing the heat of the air and other products of combustion discharged from the casing 72 to pre-heat the air delivered to the casing and thus 40 reduce the amount of fuel required to heat the liquid in the element 67. As here shown, the air is delivered to the lower portion of the casing through a supply conduit 85 and is discharged from the upper end of the casing through a 45 conduit 86. In order to utilize the heat in the conduit 86 to raise the temperature of the air in the conduit 85 I have arranged in the conduit 85 a heat exchange element or coil 87 and in the conduit 86 a heat exchange element or coil 88, these 50 coils being connected in a circuit including a pipe 89 and a pump 90, which circulates a liquid through the circuit. In the present arrangement the pump discharges through a pipe 91 into a receptacle 92 which is connected with the coil 88 and the flow of liquid from the receptacle to the coil is controlled by a valve 93. It will be apparent that the liquid passes through both conduits, 85 and 86, in a direction opposite to the directions of flow of air or other fluid in those 55 conduits, and the rate of flow of the liquid through the circuit is so controlled, by the pump 90 and the valve 93, that the liquid in the element 88 will pass from the conduit 86 at a relatively high 60 temperature, which may approach the temperature of the air or other products of combustion entering that conduit, and the air passing through the conduit 85 will be heated by the hot liquid circulating through the element 87 to a 65 relatively high temperature and will be dis- 70 75

charged into the heater casing 82 at a temperature approaching the temperature of the liquid entering the element or coil 87. consequently the air enters the heater casing at a high temperature and a small supply of fuel will serve to impart thereto such additional rise in temperature as may be desired. In the arrangement here shown I have also provided means for utilizing room air as the source of air supply for the heater 5 casing and for this purpose the air supply conduit 85 is connected with the outlet conduit 58 leading from the casing 45. While the air is discharged from this casing 45 at a temperature somewhat lower than room temperature it will nevertheless, in cold weather, be substantially higher than outside temperature and the heat available in the heat exchange element 87 will raise this air to a higher temperature than it would raise the cold outside air. The discharge conduit 86 for the 10 heater casing is also shown as connected with the outlet 58 but this is largely a matter of convenience to avoid two outlet openings in the wall of the building. Dampers 94 and 95 are provided for controlling the flow of air through the 15 conduits.

In that form of the apparatus shown in Fig. 3 the air is withdrawn from the room and returned thereto by means of a main conduit 101 and a portion of this conduit, as shown at 102, constitutes the casing of a heat exchange device or humidifier for modifying the dew point temperature of the room air before it is returned to the room. Mounted in the casing 102 is a distributor 103 arranged to discharge finely divided liquid 20 through the casing in a direction opposite to the direction of the flow of air thereto. Preferably a baffle is arranged in the casing below the distributor and the liquid is caused to flow over this baffle to expose relatively large surface areas 25 thereof to the action of the air. This baffle may be of any suitable character but the type of baffle shown in detail in Fig. 4 is very efficient. As there shown the distributor comprises a series of downwardly directed nozzles 104 which receive 30 liquid from the pipe 105 and have at their lower ends small outlets 106 through which the liquid will be slowly discharged. Arranged beneath the distributor are a plurality of series of plates 107, which are preferably of material having 35 high heat conductivity, such as copper. The plates of the upper series are slightly inclined and are arranged beneath the corresponding nozzles 104 so that the liquid will drip from said nozzles onto the inclined surfaces of the plates 40 and spread over the same in a thin film. The plates of each lower series are inclined in a direction opposite the direction of inclination of the plates of the next higher series and are arranged beneath the corresponding plates of the 45 next higher series to receive the water therefrom. The plates of each series are spaced relatively short distances apart and, due to their inclination, provide a series of relatively narrow tortuous passageways through the baffle. The air 50 passing through each of these passageways will contact with a wet surface on one side of the passageway and with a dry surface on the other side of the passageway, but as the plates have a large heat conductivity the dry sides thereof will 55 be maintained at a temperature approaching that of the liquid and when the liquid is cooler than the air the dry sides of the plates will absorb considerable quantity of heat from the air. Due to this arrangement a relatively small quantity of liquid will suffice to cause the air to be

discharged at a dew point temperature approximating that of the incoming liquid.

The liquid may be supplied to the distributor from any suitable source of supply and, in the arrangement shown water is taken from a well 5 by a pump 108 and delivered through a pipe 109 to a main reservoir 110. The delivery of the water from the well, or other source of supply, is so controlled as to maintain the water in the reservoir 110, at or above a predetermined level. 10 In the present construction the pump is operated by an electric motor 111 and a snap switch 112 is interposed in the circuit of the pump motor and is controlled by a float 113 in the reservoir to cause the pump to operate intermittently at 15 such intervals as may be necessary to maintain the desired supply of water in the reservoir. The level of the water in the reservoir fluctuates through rather a wide range and if the water was delivered directly from the reservoir to the distributor 103 the head or pressure on the distributor would vary with changes of level in the reservoir. In order to maintain a constant head on the distributor I have provided a second or supplemental reservoir 114 to which the water is 20 delivered by gravity from the main reservoir 110. The outlet for the main reservoir is controlled by a valve 115 which is actuated by a float 116 in the supplemental reservoir, the arrangement of the valve and float being such as to maintain the 25 water in the reservoir 114 at a substantially constant level. The water is discharged from the supplemental reservoir 114 through a pipe 117 which is connected by a pipe 118 with the distributor 103, the pipe 118 being provided with a 30 cut-off valve 119.

It is not always desirable to continuously operate the heat exchange device or humidifier in the portion 102 of the main conduit and I have here shown means for controlling the operation 40 of that device in accordance with the temperature of the room air. For this purpose a valve 120 is inserted in the pipe 118 leading to the distributor 103 and is connected through a lever system, comprising a pivoted arm 121, with an 45 expandable device or bellows 122 which is connected with a fluid bulb 123 arranged in the main conduit 101, so that when the temperature of the room air is lowered the bellows will contract to close the valve and when the temperature 50 rises to a predetermined degree the bellows will expand to open the valve. Preferably a spring 124 is connected with the pivoted arm 121 and so arranged that when that arm has been moved past an intermediate position the spring will 55 quickly complete the movement of the arm to either open or close the valve.

The water which is passed through the air in the portion 102 of the conduit 101 may be utilized to modify the temperature of the room air before it enters said portion of the conduit. In the construction shown the water from the distributor 103 after passing through the air is delivered to a receptacle or catch basin 125 from which it is discharged through a pipe 126 to a tubular 60 element 127 arranged in the conduit 101 in advance of the portion 102 thereof and from which the liquid is discharged through a pipe 128 to waste. The arrangement is such that the liquid flows through the tubular element 127 in a direction opposite the flow of the air through the conduit, thus modifying the temperature of the air and enabling the desired dew point temperature to be imparted thereto in the portion 65 102 of the conduit by a smaller quantity of water 70 75

than would otherwise be necessary. A valve 129 in the pipe 128 is controlled by a float 130 in the catch basin 125 to maintain the tubular element full of water at all times.

5 A supply of fresh air at desired dew point temperature is constantly delivered to the room, and, in the present construction, a fresh air conduit 230 is connected with the main conduit 101 above the distributor 103 and has an enlarged 10 portion 231 forming a casing, the lower end of which is open to provide an inlet for fresh air, which may be received from a window 232 in the basement or other compartment in which the apparatus is installed. A distributor 233 is arranged 15 in the casing 231 to discharge liquid therethrough in a direction opposite to the flow of the air and is connected by a pipe 234 with the supplemental reservoir 114. If desired, baffles 235 may be arranged in the casing 231 beneath 20 the distributor and, as here shown, the distributor and baffle are of the types illustrated in Fig. 4. The water is discharged from the casing 231 to a receptacle or catch basin 236 from which it is discharged through a pipe 237. A valve 238 in 25 the pipe 237 is controlled by a float 239 in the catch basin to maintain a substantial quantity of water in the catch basin at all times. The rate of flow of the water through the casing is automatically controlled according to the wet 30 bulb temperature of the incoming fresh air and for that purpose a regulating valve 240 is interposed in the pipe 234 and is controlled by an expansible element or bellows 241 connected with a fluid bulb 242 in the catch basin 236. The air 35 passing through the casing in contact with the water will be discharged therefrom at a dew point temperature approaching the temperature of the incoming water, and the water will be discharged from the casing at a temperature approaching the wet bulb temperature of the incoming fresh air. Consequently the thermostatically controlled valve 240 will be operated in accordance with the wet bulb temperature of the incoming air. A cut-off valve 243 is also mounted in the pipe 234 to completely interrupt the flow of liquid therethrough when desired.

Water from the catch basin 236 may be discharged to waste but I prefer to modify the temperature thereof in accordance with the wet bulb temperature of the room air and again utilize the same. I have therefore, connected the discharge pipe 237 with a pump 244 by which the water is delivered through a pipe 245 to a distributor 246 in the casing 247 of a heat exchange device which is supplied with room air. As here shown, the lower end of this casing opens into a receptacle 248, the upper portion of which is in open communication with a conduit 249 connected with the main conduit 101 at a point in 55 advance of the heat exchange device therein. If desired, a motor operated fan 250 may be arranged in the conduit 249 to insure a proper flow of room air through the same. This room air enters the open lower end of the casing and is 60 discharged from the top of the casing through a waste conduit 251. If desired, a baffle 252 may be arranged in the casing beneath the distributor and, in the present instance, the distributor and baffle are of the types shown in Fig. 4. The 65 lower portion of the receptacle 248 constitutes a catch basin for the water discharged from the casing and the outlet for this catch basin is connected with a pipe 253 leading to the catch basin 125 in the main conduit 101. The water 70 is delivered to the catch basin 248 at a tempera- 75

ture approaching the wet bulb temperature of the room air and passes therefrom to the catch basin 125 and then through the tubular heat exchange element 127 in the main conduit. If the heat exchange and humidifying device in 5 the portion 102 of the main conduit is in operation the water from the catch basin 248 will be mixed with the water from the distributor 103 before it is delivered to the tubular element 127. The outlet for the catch basin 248 is connected 10 by a pipe 254 with the distributor 233 in the fresh air casing 231, this pipe being provided with a valve 255. When water is being delivered from the supplemental reservoir 114 to the distributors 103 and 233 the valve 255 will be closed and the apparatus will operate in the manner above described, but by closing the valve 243 in the pipe 234, which connects the supplemental reservoir with the distributor 233, closing the valve 256 in the pipe 253 and opening the valve 255 in the pipe 254 the apparatus may be operated on a closed circuit, the water circulating repeatedly through the fresh air casing 231 and the room air casing 247. In warm weather the valve 255 will be closed and cool fresh water will be supplied to 20 the distributor 103 and 233 and inasmuch as the room air will then be at a temperature lower than the exterior air the water passing through the room air casing 247 will be cooled and delivered to the heat exchange element 127 to cool the 25 room air in the conduit 101. In cool weather it is usually desirable to interrupt the supply of cool water, either by stopping the pump or by closing the valves 119 and 243, and to then open the valve 255 to supply the distributor 233 in the 30 fresh air casing with water which has passed through the room air casing 247, the temperature of which has been accordingly raised. However, if desired, the apparatus as a whole may be utilized in cold weather and the fresh water may 35 be heated as by means of a coil 257 in the main reservoir 110.

Also if desired the apparatus as a whole may be operated on a closed circuit by connecting the liquid discharged pipe 128 for the tubular element 127, with the pump 111, by means of a pipe 258, and closing a waste valve 259 in the pipe 128 and also closing a valve 260 in the pipe connecting the pump with the well or other source of supply. A valve 261 serves to prevent the flow 45 of liquid through the pipe 258 when the pump is connected with the well. When the pump is connected with the waste pipe 128 and the apparatus as a whole is operated on a closed circuit the coil 257 in the main reservoir 110 may be utilized for 50 either heating or cooling the water as may be necessary.

In that form of apparatus shown in Fig. 5 the device for imparting the desired dew point temperature to the fresh air which is to be delivered to the room is of the recirculating type and is provided with means for cooling the liquid as it circulates through the device. In this form of apparatus a main conduit 135 receives the air from and returns the same to the room in the 55 manner above described and is provided with a fan 136 for circulating air through the same. A waste air conduit 137 leads from the conduit 135, in the present instance at a point adjacent to the inlet end of the conduit 135. This waste air conduit is connected with the air inlet 138 of a heat exchange device 140 comprising a casing 139 having that end opposite the air inlet 138 connected with an outlet conduit 141 leading to the exterior 60 of the building. Water or other suitable liquid 65

is delivered to the casing 139 through a distributor 142 and passes, preferably over a baffle 143, in a direction opposite the direction of flow of the air through the casing and is delivered to a catch basin 144. The water is withdrawn from the catch basin 144 by a pump 145 which delivers the same through a pipe 146, a cooling element 147 and pipe 148 to a distributor 149 in the upper end of the casing 150 of a second heat exchange device. The casing 150 has at its lower end an inlet 151 for fresh air and at its upper end an outlet 152 for air, which is connected by a conduit 153 with the main conduit 135. The water passes, preferably over a baffle 154, through the casing 150 in a direction opposite to the direction of flow of fresh air through that casing and is discharged into a catch basin 155. A pump 156 withdraws the water from the catch basin 155 and delivers the same through a pipe 157 to the distributor 142 in the casing 139 of the heat exchange device 140. The rate of flow of the water through the two casings is controlled by the operation of the pumps and may also be further controlled according to the dew point temperature of the fresh air entering the casing 150 by means of a valve 158 which is here shown as actuated by an expansible element or bellows 159 which is connected with a bulb 160 immersed in the water in the catch basin 155, in the manner above described. The water thus circulates through an endless circuit and its temperature will be raised by the absorption of heat from the fresh air passing through the casing 150. The room air which is delivered to the casing 139 being at a lower temperature than the fresh air will absorb heat from the water as it passes through the casing 139 but ordinarily the temperature of the room air will not be low enough to impart the desired temperature to the water and I have therefore interposed in the water line between the casings 139 and 150 the cooling element 147. This cooling element comprises a refrigerating apparatus which utilizes water vapor as a cooling medium. As here shown, the cooling element 147 comprises a housing connected at its lower end with the discharge pipe 146 of the pump 145 and connected at its upper end with the pipe 148. Arranged within this housing is an evaporator 161 which may be of any suitable kind and is here shown as of a conventional type. This evaporator is connected by a pipe 162 with an injector 163. A steam generator 164 is connected by a pipe 165 with the injector 163 and the steam discharged through the injector 163 will draw vapor from the evaporator 161 and thus lower the temperature within the housing 147 in a well known manner. The steam and vapors are discharged from the injector to a condenser 166 and the condensate is delivered from the condenser to a receiver 167 which is connected by a pipe 168 with the evaporator, to provide a continuous supply of water to the evaporator. Only a portion of the water in the receiver 167 is delivered to the evaporator and the remainder of this water is returned to the generator 164. In order to introduce this water into the generator, against the pressure therein, an injector 169 is connected with the steam discharge pipe 165 by a pipe 170 and has its discharge end connected by a pipe 171 with the generator, a check valve 172 being interposed in the pipe 171 to prevent the backflow of water from the generator to the receiver. The receiver 167 is connected by a pipe 173 with the injector 169, so that water will be drawn into the injector from the receiver. In order to properly inject the

water into the generator the steam should be condensed within the injector 169 and as the water entering the injector is not always cool enough to completely condense the steam I have provided the pipe 173 with a cooling element 174 which is connected by a pipe 175 with the pipe 148 leading from the cooling element 147. Cool water is thus circulated through the cooling element 174 and is discharged therefrom through a pipe 176 which, in the present instance, leads to the catch basin 155. The cooling element 174 will thus so reduce the temperature of the water entering the injector 169 as to cause the condensation of the steam in that injector and the proper introduction of the water into the generator. By the use of this injector system I am able to circulate the water through a closed system and return the same to the generator without danger of air leaks which would destroy the vacuum which is necessary to the effective operation of the evaporator and to maintain sufficient pressure in the generator for efficient operation.

The steam generator may be of any suitable character which will provide steam in the desired amount and at the desired pressure and, as here shown, it comprises a boiler which is heated by a gas burner 177. The economical operation of the apparatus may require a variation of steam pressure according to variations in the heat content of the fresh air and I have provided means for controlling the supply of fuel to the burner 177 in accordance with the temperature of the fresh air discharged from the casing 150 to the main conduit. This is accomplished by means of a valve 178 in the fuel supply line, which valve is actuated by an expansible element or bellows 179 connected with a bulb 180 in the fresh air conduit 153. If desired, the amount of water passing through the cooling element 147 may be automatically regulated by means of a valve 181 which is actuated by a float 182 in the catch basin 155. By thus utilizing the waste room air to partially cool the circulating medium or water the amount of refrigerant necessary to maintain this water at the desired temperature is substantially reduced and the cost of operating the apparatus is correspondingly reduced.

If desired, the fresh air which is being delivered to the room at a relatively low temperature, through the conduit 153, may be utilized to pre-cool room air which is delivered to the heat exchange device 140, thereby enabling the water passing through the heat exchange device to be reduced to a lower temperature than would otherwise be possible. For this purpose I have mounted in the conduit 153 a tubular heat exchange element 210 which is connected at one end with the discharge side of a pump 211 and is connected at its other end by a pipe 212 with a similar tubular element 213 in the room air waste pipe 137, this latter element being connected at its discharge end with the intake of the pump 211. A liquid is circulated by the pump through the closed circuit thus formed and flows through the tubular elements in directions opposite the direction of flow of the air through the respective conduits. Thus the liquid is cooled in the tubular element 210 and this cool liquid flowing through the tubular element 213 absorbs heat from the room air. The temperature of the fresh air will, of course, be raised somewhat but this is not seriously objectionable because this air is passed about a cooling element 183 in the main room air conduit 135 be-

fore it is delivered to the room, and the cooling in conduit 135 is effected at a relatively high temperature and therefore the cost is relatively low. Further, by so pre-cooling the room air 5 before it is delivered to the heat exchange device 140 the water may be delivered to the refrigerating device 147 at a relatively low temperature and less refrigeration will be necessary to secure the desired temperature in the 10 water delivered to the heat exchange device 150 for fresh air.

In this form of apparatus a separate system is provided for cooling the air which has been withdrawn from the room and is to be again delivered thereto. Refrigeration may be effected much more economically at high temperatures than at low temperatures, and I have provided means for effecting the major portion of the air cooling operation at a relatively high temperature 20 and then further cooling the air to the desired low temperature by a second operation. In this manner a higher efficiency and lower cost is attained than could be attained if the air was cooled to the desired temperature at one operation. For this purpose, a cooling element or coil 183 is arranged within the main conduit 135 and supplied with a cooling medium to further cool the recirculated room air after it has been partially cooled by mixing the humidified fresh air 30 therewith. As here shown, the cooling element 183 has its lower or discharge end connected by a pipe 184 with the intake of a pump 185, the discharge side of which is connected with the housing 186 of a cooling element and the upper 35 end of this housing is connected by a pipe 187 with the lower end of the housing 188 of a second cooling element, and the upper end of this second housing is connected by a pipe 189 with the upper or inlet end of the cooling element 183 in 40 the conduit 135. The pump 185 thus serves to circulate a suitable liquid through the endless circuit which includes the two cooling or refrigerating units 186 and 188 and the liquid is thus progressively cooled and the amount of refrigerant and the cost of refrigeration is correspondingly reduced. As is well understood the cost of effecting refrigeration is proportional to the logarithm of the ratio of compression, and the higher the temperature at which refrigeration 45 is effected the higher must be the ratio of compression. By effecting refrigeration progressively a large portion of it may be effected at a lower temperature than would be possible if complete refrigeration was effected at one time or 50 by a single operation. Arranged within the housings 186 and 188 are evaporators 190 and 191 in which water may be used as the refrigerating medium. A steam generator 192 has a discharge pipe 193 which is separately connected with two 55 injectors 194 and 195, the injector 195 being preferably of a somewhat larger size than the injector 194. The injector 194 is connected by a pipe 196 with the evaporator 190 and the passage of steam through that injector serves to 60 draw vapor from the evaporator and to reduce the temperature of the liquid therein. The injector 195 is connected by a pipe 197 with the evaporator 191 and the passage of steam through the injector 195 serves to draw vapors from the 65 evaporator 191. Both injectors have their discharge ends connected with a condenser 198 which discharges into a receiver 199. This receiver is connected by a pipe 200 and suitable branches with the evaporators 190 and 191 so 70 that a portion of the liquid of condensation is 75

returned to the evaporators. The remainder of the water in the receiver 199 is returned through a pipe 201 to the steam generator 192, the water being introduced into the generator by an injector 202 and a cooler 203 being interposed in the pipe 201 and connected with the pipes 189 and 184 to so cool the liquid as to condense the steam in the injector 202, in the manner hereinbefore described in connection with the injector 169. It will be apparent that the liquid which is discharged from the cooling element 183 is first partially cooled in the housing 186 and is then further cooled in the housing 188, the larger size of the injector 195 serving to draw a greater amount of vapor from the evaporator 191 and thus maintain the temperature in the housing 188 substantially lower than the temperature in the housing 186. The steam generator here employed may also be of any suitable character and is shown as a boiler heated by a gas burner 204 and the steam pressure is automatically controlled in accordance with the room temperature by means of a valve 205 in the gas supply pipe which is controlled by a thermostatic device comprising a bulb 206 in the main conduit 135. While the apparatus of Fig. 5 is shown as a cooling apparatus, it will be obvious that it may be combined with a suitable heater, as in the manner shown in Fig. 1, and when so combined the apparatus would operate the year round to maintain the room air in the proper condition, the refrigerating device being employed in warm weather and the heating device being employed in cool weather.

It will be obvious that the various elements and sub-combinations of the several forms of the apparatus here illustrated are, in part at least, interchangeable and that these elements and sub-combinations may be grouped in various arrangements or combinations other than those here illustrated.

While I have shown and described certain forms of apparatus for carrying out my method of air conditioning I wish it to be understood that I do not desire to be limited to the details of either the method or the apparatus as various modifications may occur to a person skilled in the art.

Having now fully described my invention, what I claim as new and desire to secure by Letters Patent is:

1. A method of supplying conditioned air to a room which comprises withdrawing air from said room, causing a supply of fresh air to flow through a chamber, causing liquid to flow through said chamber in a direction opposite the direction of flow of fresh air and in contact therewith, thereby modifying the temperature of both said fresh air and said liquid, utilizing said liquid after it has passed through said fresh air to modify the temperature of air withdrawn from said room, and delivering said fresh air and said modified room air to said room.

2. The method of supplying conditioned air to a room which comprises withdrawing air from said room, passing a portion of the withdrawn room air in heat exchanging relation to a liquid to modify the temperature of the latter, passing fresh air in heat exchanging relation to the modified liquid to modify the temperature of the fresh air, circulating a liquid through a closed circuit, modifying the temperature of the liquid in a portion of said circuit, passing withdrawn room air about another portion of said circuit to modify the temperature of said room air and de-

livering said modified fresh air and said modified room air to the room.

3. The method of supplying conditioned air to a room which comprises withdrawing air from said room, passing a portion of the withdrawn room air in heat exchanging relation to a liquid to modify the temperature of the latter, passing fresh air in heat exchanging relation to the modified liquid to modify the temperature of the fresh air, circulating a liquid through a closed circuit, modifying the temperature of the liquid in a portion of said circuit, automatically controlling the modification of the temperature of the liquid in said circuit in accordance with the temperature of the room air, passing withdrawn room air about another portion of said circuit to modify the temperature of said room air and delivering said modified fresh air and said modified room air to the room.

20 4. The method of supplying conditioned air to a room which comprises circulating a liquid through an endless circuit, subjecting a portion of said circuit to the action of a hot fluid to heat the liquid therein, withdrawing air from said room and subjecting the air so withdrawn to the action of another portion of said circuit to cause the air to be heated thereby, subjecting a supply of fresh air to the action of a liquid to modify the dew point temperature of said air and delivering said fresh air and the heated room air to said room.

25 5. The method of supplying conditioned air to a room which comprises withdrawing air from said room, passing fresh air through a chamber, delivering water from a source of water supply to said chamber at a low temperature, causing said water to flow through said chamber in a direction opposite the direction of flow of said fresh air and causing relatively large surface areas 40 thereof to contact with said fresh air in said chamber, automatically controlling the delivery of water to said chamber in accordance with the wet bulb temperature of the air entering said chamber to supply said water in such quantities 45 as to cause said fresh air to be discharged from said chamber at a dew point temperature approaching the temperature of the water delivered to said chamber, mixing said fresh air with air withdrawn from said room, and delivering the mixture to said room.

50 6. A method of supplying conditioned air to a room which comprises withdrawing air from said room, passing fresh air through a chamber, delivering water from a source of water supply to said chamber at a low temperature, causing said water to flow through said chamber in a direction opposite to the direction of flow of said fresh air, controlling the flow of said water to cause relatively large surface areas thereof to contact with the fresh air in said chamber, controlling the rate of flow of said water through said chamber to cause said fresh air to be discharged from said chamber at a dew point temperature approaching the temperature of the water delivered to said chamber, and to cause said water to be discharged from said chamber at a temperature approaching the wet bulb temperature of the fresh air entering said chamber, causing the water discharged from said chamber to pass in heat exchange relation to air withdrawn from said room to modify the dry bulb temperature of the latter, and delivering said fresh air and the modified room air to said room.

70 7. A method of supplying conditioned air to a room which comprises withdrawing air from said

room, causing a supply of fresh air to flow through a chamber, causing liquid to flow through said chamber in a direction opposite to the direction of flow of said fresh air and in contact therewith, controlling the rate of flow of said liquid to cause said fresh air to be discharged from said chamber at a dew point temperature approaching the temperature of the liquid entering the chamber, and to cause the liquid to be discharged from said chamber at a temperature approaching the wet bulb temperature of the air entering said chamber, controlling the discharge of liquid from said chamber according to the temperature of the room air to cause said liquid to be discharged to waste or to be circulated through withdrawn room air to modify the temperature of the latter, and delivering said fresh air and said modified room air to said room.

20 8. A method of supplying conditioned air to a room which comprises withdrawing air from said room, passing a portion of said withdrawn air through a chamber, passing a liquid through said chamber in a direction opposite the direction of flow of said air and in heat exchange relation to said air to cool said liquid, subjecting said liquid 25 to the action of a cooling medium to further cool the same, passing said cooled liquid through a second chamber, passing fresh air through said second chamber in a direction opposite to the direction of flow of said liquid to lower the dew point temperature of said fresh air, and delivering said fresh air to said room.

25 9. A method of supplying conditioned air to a room which comprises withdrawing air from said room, passing a portion of said withdrawn air through a chamber; passing a liquid through said chamber in a direction opposite the direction of flow of said air and in heat exchange relation to said air to modify the temperature of said liquid, then passing said liquid through a second chamber, passing fresh air through said second chamber in a direction opposite to the direction of flow of said liquid and in heat exchange relation to said liquid to modify the dew point temperature 40 of said fresh air, then passing said fresh air through another chamber, passing other liquid through the last mentioned chamber in a direction opposite to the direction of flow of said fresh air and in heat exchange relation to said fresh air to further modify the dew point temperature 45 of said fresh air, and delivering said fresh air to said room.

50 10. A method of supplying conditioned air to a room which comprises withdrawing air from said room, circulating a liquid in an endless circuit, passing a portion of the air withdrawn from said room through the liquid in a part of said circuit and in a direction opposite the direction of flow of said liquid to lower the temperature of said liquid, subjecting said liquid to the action 55 of a cooling medium to further lower its temperature, passing fresh air through the cooled liquid in another part of said circuit and in a direction opposite the flow of said liquid to lower the dew point temperatures of said fresh air, controlling the action of said cooling medium in accordance with the temperature of the fresh air discharged from the last mentioned part of said circuit, and delivering said fresh air to said room.

60 11. A method of supplying conditioned air to a room which comprises withdrawing air from said room, circulating a liquid in an endless circuit, passing a portion of the air withdrawn from said room through the liquid in a part of said circuit and in a direction opposite the direction of 65

- flow of said liquid to lower the temperature of said liquid, subjecting said liquid to the action of a cooling medium to further lower its temperature, passing fresh air through the cooled liquid
- 5 6 in another part of said circuit and in a direction opposite the flow of said liquid to lower the dew point temperature of said fresh air, circulating a liquid through a second endless circuit, passing a portion of the air withdrawn from said room
- 10 10 about a part of said second circuit, subjecting the liquid in another part of said second circuit to successive actions of a cooling medium to progressively reduce the temperature thereof, and delivering said fresh air and the last mentioned
- 15 15 portion of the withdrawn room air to said room.
12. A method of supplying conditioned air to a room which comprises circulating a liquid through an endless circuit, withdrawing air from said room, passing said air about a portion of said
- 20 20 circuit in a direction opposite the direction of flow of the liquid therein and returning said air to said room, causing the products of combustion from a heater to pass about another portion of said circuit in a direction opposite the direction of flow of the liquid therein, circulating a liquid
- 25 25 through a second endless circuit, causing air withdrawn from said room to pass through the liquid in a portion of said second circuit in a direction opposite to the direction of flow of the liquid
- 30 30 therein, causing fresh air to pass through the liquid in another portion of said second circuit in a direction opposite the direction of flow of the liquid therein, and delivering said fresh air and the first mentioned room air to said room.
- 35 35 13. A method of heating air or the like which comprises circulating a liquid through an endless circuit, passing the air to be heated about a portion of said circuit, passing products of combustion from a heater about another portion of
- 40 40 said circuit, circulating a liquid in a second endless circuit, passing the products of combustion which have passed the first mentioned circuit about a portion of said second circuit, and passing air about another portion of said second circuit and delivering the last mentioned air to said heater.
- 45 45 14. An apparatus for supplying conditioned air to a room comprising a main conduit for withdrawing air from said room and for delivering modified air to said room, means for circulating a liquid in a closed circuit through said main conduit, means external to said main conduit to modify the temperature of the liquid in said circuit, a casing, means for passing air from said main conduit through said casing, means for passing a liquid through said casing in heat exchanging relation to said air to modify the temperature of said liquid, a second casing, means for passing the liquid from the first mentioned
- 50 50 casing through said second casing, and means for passing fresh air through said second casing in heat exchanging relation to the liquid therein to modify the temperature of said fresh air and for delivering the fresh air from said second casing to said main conduit.
- 55 55 15. An apparatus for supplying conditioned air to a room comprising a main conduit for withdrawing air from said room and for delivering modified air to said room, means for circulating a liquid in a closed circuit through said main conduit, means external to said main conduit to modify the temperature of the liquid in said circuit, a casing, means for passing air from said main conduit through said casing, means for passing a liquid through said casing in heat exchange
- 60 60
- 65 65
- 70 70

ing relation to said air to modify the temperature of said liquid, a second casing, means for passing the liquid from the first mentioned casing through said second casing, means for passing fresh air through said second casing in heat exchanging relation to the liquid therein to modify the temperature of said fresh air and for delivering the fresh air from said second casing to said main conduit, and means controlled in accordance with the wet bulb temperature of the fresh air entering said second casing to regulate the flow of the last mentioned liquid.

16. An apparatus for supplying conditioned air to a room comprising a main conduit for withdrawing air from said room and for delivering modified air to said room, a temperature modifying device, an endless circuit for a liquid having a part in said main conduit and a part in heat exchange relation to said temperature modifying device, a casing, means for withdrawing air from said main conduit and passing said air through said casing, means for passing a liquid through said casing in contact with the air therein, a second casing, means for passing a liquid from the first mentioned casing through said second casing, means for passing fresh air through said second casing in contact with the liquid therein and for delivering said fresh air to said main conduit, and a single device for circulating air through said main conduit and said casings.

30 17. An apparatus for supplying conditioned air to a room comprising a main conduit for withdrawing air from said room and for delivering modified air to said room, a heater, heat exchange elements mounted respectively in said heater and said main conduit and connected in an endless circuit for liquid, and means for supplying air to said heater from said main conduit.

35 18. An apparatus for supplying conditioned air to a room comprising a main conduit for withdrawing air from said room and for delivering modified air to said room, a heater, heat exchange elements mounted respectively in said heater and said main conduit and connected in an endless circuit for liquid, and means controlled in accordance with the temperature of the liquid in said circuit to control the rate of flow of said liquid.

40 19. In an apparatus for supplying conditioned air to a room comprising a main conduit for withdrawing air from said room and for delivering modified air to said room, a heater, heat exchange elements mounted respectively in said heater and said main conduit and connected in an endless circuit for liquid, means controlled in accordance with the temperature of the room air to automatically control the operation of said heater, a casing, means for passing air from said main conduit through said casing, means for passing a liquid through said casing in heat transferring relation to said air to modify the temperature of said liquid, a second casing, means for passing the liquid from the first mentioned casing through said second casing, and means for passing fresh air through said second casing in heat exchange relation to the liquid therein to modify the temperature of said fresh air and for delivering the fresh air from said second casing to said main conduit.

45 20. In an apparatus for supplying conditioned air to a room, a casing having near one end thereof an inlet for fresh air and having near the other end thereof an outlet for fresh air, means for delivering a liquid to said casing adjacent to said outlet and causing said liquid to flow toward said

inlet, a baffle in said casing over which said liquid and said air flow in opposite directions, means for controlling the rate of flow of said liquid through said casing in accordance with the wet bulb temperature of the air entering said casing to cause said fresh air to be discharged from said casing at a temperature approaching the temperature of the liquid entering said casing, and means for introducing said fresh air into said room.

10 21. In an apparatus for supplying conditioned air to a room, a casing having near its lower end an inlet for fresh air and having near its upper end an outlet for fresh air, means for passing a liquid through said casing in a direction opposite the direction of flow of said air and causing relatively large surface areas of said liquid to contact said air, a receptacle below said fresh air inlet to receive the liquid from said casing, means controlled by the temperature of the liquid in said receptacle to so control the rate of flow of said liquid through said casing that said fresh air will be discharged through said outlet at a dew point temperature approaching the temperature of the liquid entering said casing, and means for introducing said fresh air into the room.

22. In an apparatus for supplying conditioned air to a room, a casing having near one end thereof an inlet for fresh air and having near the other end thereof an outlet for fresh air, means for passing a liquid through said casing in a direction opposite the direction of flow of said air and causing relatively large surface areas of said liquid to contact said air, a valve to control the rate of flow of said liquid, said valve having a permanently open restricted passageway, means controlled in accordance with the wet bulb temperature of the fresh air entering said casing to vary the capacity of the passageway in said valve, whereby said fresh air will be discharged from said casing at a dew point temperature approximating the temperature of the incoming liquid, and means for delivering said fresh air to a room.

23. In an apparatus for supplying conditioned air to a room, a casing having near one end thereof an inlet for fresh air and having near the other end thereof an outlet for fresh air, means for passing a liquid through said casing in a direction opposite the direction of flow of said air and causing relatively large surface areas of said liquid to contact said air, means for so controlling the rate of flow of said liquid through said casing that the fresh air will be discharged through said outlet at a dew point temperature approaching the temperature of the liquid entering said casing, and the liquid will be discharged from said casing at a temperature approaching the wet bulb temperature of the fresh air entering said casing, means for delivering fresh air from said casing to said room, means comprising a conduit for withdrawing air from said room and returning the same to said room, a cooling element in said conduit, and means for circulating the liquid discharged from said casing through said cooling element.

24. In an apparatus for supplying conditioned air to a room, two casings, means for causing liquid to pass through said casings successively, means for withdrawing air from said room and passing the same through one of said casings in direct contact with said liquid and in a direction opposite the direction of flow of said liquid to modify the temperature of the latter, means for passing fresh air through the other of said casings in direct contact with said liquid and in a direction opposite the direction of flow of said liquid

to modify the dew point temperature of said air, a third casing, means for passing said modified fresh air through said third casing, means for passing water from an exterior source of supply through said third casing in direct contact with said fresh air and in a direction opposite the direction of flow of said fresh air to modify the dew point temperature of said fresh air, means controlled in accordance with the wet bulb temperature of the fresh air entering said third casing to control the quantity of water delivered to said third casing, and means for delivering fresh air from said third casing to said room.

25. In an apparatus for supplying conditioned air to a room, two casings, means for causing liquid to pass through said casings successively, means for withdrawing air from said room and passing the same through one of said casings in a direction opposite the direction of flow of said liquid to modify the temperature of said liquid, means for passing fresh air through the other of said casings in direct contact with said liquid and in a direction opposite the direction of flow of said liquid to modify the dew point temperature of said air, a third casing, means for passing said modified fresh air through said third casing, means for passing a liquid through said third casing in direct contact with said fresh air and in a direction opposite the direction of flow of said fresh air to further modify the dew point temperature of said fresh air, means for delivering said fresh air from said third casing to said room, means comprising a conduit for withdrawing air from said room and returning the same thereto, and means for circulating the liquid discharged from said third casing through said conduit.

26. In an apparatus for supplying conditioned air to a room, two casings, means for causing liquid to pass through said casings successively, means for withdrawing air from said room and passing the same through one of said casings in a direction opposite the direction of flow of said liquid to modify the temperature of said liquid, means for passing fresh air through the other of said casings in direct contact with said liquid and in a direction opposite the direction of flow of said liquid to modify the dew point temperature of said air, a third casing, means for passing said modified fresh air through said third casing, means for passing a liquid through said third casing in direct contact with said fresh air and in a direction opposite the direction of flow of said fresh air to further modify the dew point temperature of said fresh air, means for delivering said fresh air from said third casing to said room, means comprising a conduit for withdrawing air from said room and returning the same thereto, means for circulating a liquid through a closed circuit having a part arranged in said conduit, and means for heating the liquid in another part of said circuit.

27. In an apparatus for supplying conditioned air to a room, means for passing fresh air through a liquid to modify the dew point temperature of said air, means for delivering the modified fresh air to said room, a conduit for withdrawing air from said room and returning the same to said room, a tubular element to modify the temperature of the air in said conduit, and means for circulating said liquid through said tubular element.

28. In an apparatus for supplying conditioned air to a room, means for passing fresh air through a liquid to modify the dew point temperature of said air, means for delivering the modified fresh air to said room, a conduit for withdrawing air

- from said room and returning the same to said room, a tubular element to modify the temperature of the air in said conduit, a means for circulating said liquid through said tubular element, 5 and means controlled by the temperature of the air in said room to control the amount of liquid circulated through said tubular element.
29. In an apparatus for supplying conditioned air to a room, means for passing fresh air through 10 a liquid to modify the dew point temperature of said air, means for delivering the modified fresh air to said room, a conduit for withdrawing air from said room and returning the same to said room, a tubular element to modify the temperature 15 of the air in said conduit, a liquid heating apparatus, and means for circulating through said tubular element either liquid from said heating apparatus or liquid which has been passed through said fresh air.
30. In an apparatus for delivering conditioned air to a room, a casing, means for passing fresh air and a liquid through said casing in opposite directions to modify the dew point temperature of said fresh air, means for delivering the modified 20 fresh air to said room, a receptacle to receive liquid from said casing, a discharge pipe leading from said receptacle, a conduit for withdrawing air from said room and returning the same to said room, a tubular element in said conduit, a 25 liquid heater comprising a second tubular element, means for interchangeably connecting said discharge pipe and said second tubular element with said first mentioned tubular element and for causing liquid to circulate through the first mentioned tubular element, an air inlet and an air outlet for said heater, and means for circulating a liquid through said inlet and said outlet successively to cause heat from the outgoing products of combustion to be transferred to the incoming air. 30
31. In an apparatus for supplying conditioned air to a room, a casing having an inlet and an outlet for air, a discharge conduit to conduct air from said casing to said room, means for passing a liquid through said casing in contact with said 35 air to lower the dew point temperature of said air, a second casing having an inlet and an outlet for air, a conduit to conduct air from said room to the inlet of said second casing, means for passing liquid which is discharged from the first mentioned casing through said second casing, tubular elements arranged in the respective conduits, and means for circulating a liquid through said tubular elements successively in a direction opposite the directions of flow of the air in said conduits 40 to cause the temperature of the air in the last mentioned conduit to be modified before it is delivered to said second casing.
32. In an apparatus for supplying conditioned air to a room, a conduit to deliver air to said room, 45 a distributor to discharge liquid through the air in a portion of said conduit, a tubular element arranged in the path of air which is being delivered to said room to modify the temperature thereof, and means for causing said liquid to circulate through said tubular element after it has passed through the air in said portion of said conduit.
33. In an apparatus for supplying conditioned air to a room, a conduit for withdrawing air from 50 said room and returning the same thereto, a tubular element arranged in said conduit, a casing having an inlet for fresh air and an outlet connected with said room, means for passing liquid through said casing in contact with the air there- 55 in, a second casing, means for passing air which has been withdrawn from said room through said second casing, means for passing liquid discharged from the first mentioned casing through said second casing, and means for delivering liquid discharged from said second casing to said tubular 60 element.
34. In an apparatus for supplying conditioned air to a room, a conduit for withdrawing air from said room and returning the same thereto, a tubular element arranged in said conduit, a casing having an inlet for fresh air and an outlet connected with said room, means for passing liquid through said casing in contact with the air therein, a second casing, means for passing air which has been withdrawn from said room through said second casing, means for passing liquid discharged from the first mentioned casing through said second casing, and operable means for causing the liquid discharged from said second casing to be delivered either to said tubular element or to the first mentioned casing. 65
35. In an apparatus for supplying conditioned air to a room, an air conduit, a distributor to discharge liquid through a portion of said conduit in a direction opposite the direction of flow of air therethrough, a series of plates arranged below said distributor, each plate having an inclined surface to receive liquid from said distributor, and a second series of plates below the first mentioned series, each plate of said second series being inclined in a direction opposite the direction of inclination of the plates of the first mentioned series and arranged to receive liquid from the adjacent plate of said first mentioned series. 70
36. In an apparatus for supplying conditioned air to a room, an air conduit, a distributor to discharge liquid through a portion of said conduit in a direction opposite the direction of flow of air therethrough, and a plurality of series of heat 75 conducting plates arranged one above the other beneath the distributor, the plates of each series being spaced one from the other and the plates of adjacent series being inclined in opposite directions to form relatively narrow tortuous air channels, the plates of the uppermost series being arranged to receive liquid from said distributor and the plates of each lower series being arranged to receive liquid from the corresponding plates of the next higher series. 80
37. In an apparatus for supplying conditioned air to a room, a casing having an inlet and an outlet for air, means for passing air from said room through said casing, means for passing water through said casing in a direction opposite the direction of flow of said air, an evaporator, a steam generator, an injector connected with said generator and said evaporator to draw vapor from the latter, a condenser connected with said injector, means for delivering a portion of the water 85 from said condenser to said evaporator, means for delivering another portion of the water from said condenser into said steam generator, a housing enclosing said evaporator, means for passing water delivered from said casing through said housing, a second casing having an inlet for fresh air and an outlet for air, means for passing water from said evaporator housing through said second casing in a direction opposite the direction of flow of air through said second casing, means for 90 delivering air from the outlet of said second casing to said room, and means for delivering the water discharged from said second casing to the first mentioned casing. 95
38. In an apparatus for supplying conditioned 75

air to a room, an air conduit leading to said room, a cooling element arranged within said conduit, two refrigerating units each comprising an evaporator and a housing enclosing said evaporator, means for connecting said housings one to the other, means for connecting one of said housings with the inlet end of said cooling element, means for connecting the other of said housings with the discharge end of said cooling element and for circulating water through said housings and said cooling element, a steam generator, a steam pipe leading from said generator, two injectors separately connected with said steam pipe and respectively connected with the two evaporators, a condenser connected with said injectors, means for delivering a portion of the water from said condenser to said evaporators, and means for delivering another portion of the water from said condenser to said steam generator.

39. In an apparatus for delivering conditioned air to a room, an air conduit leading to said room, a cooling element arranged in said conduit, an evaporator, a housing enclosing said evaporator and connected with the discharge end of said cooling element, a second evaporator and a second housing enclosing said second evaporator, means for connecting said housings one to the other, and means for connecting said second housing with the inlet end of said cooling element, a pump for circulating water through said housings and said cooling element, a steam generator, a steam pipe leading from said generator, an injector connected with said steam pipe and with the first mentioned evaporator, a second injector of greater capacity than the first mentioned injector connected with said steam pipe and with the second evaporator, a condenser connected with both injectors, a receiver connected with said condenser, and means for connecting said receiver

with both evaporators, a third injector connected with said steam pipe and with said steam generator, means for delivering water from said receptacle to said third injector, and means for cooling the water before it is delivered to said 5 third injector.

40. In an apparatus for supplying conditioned air to a room, means comprising a conduit for withdrawing air from said room and returning the same thereto, means for progressively modifying the temperature of the air passing through said conduit including a distributor to discharge finely divided liquid through the air in a portion of said conduit, a tubular element arranged in said conduit in advance of that portion thereof 15 through which said liquid is discharged, means for causing the liquid which has passed through said portion of said conduit to circulate through said tubular element.

41. In an apparatus for supplying conditioned 20 air to a room, a vertical casing, means for causing water to flow downwardly through said casing, means within said casing to spread said water into thin sheets and to retard the flow thereof, means for causing air withdrawn from said room 25 to flow upwardly through said casing, a second vertical casing, means to deliver said water from the first mentioned casing to said second casing and to cause the same to flow downwardly there-through, means within said second casing to 30 spread said water into thin sheets and to retard the flow thereof, means to cause fresh air to flow upwardly through said second casing, means controlled in accordance with the wet bulb temperature of the fresh air entering said second casing 35 to regulate the delivery of water to the first mentioned casing, and means for delivering said fresh air from said second casing to said room.

EDWARD T. TURNER.
